CLAIM

The ornamental design for a vehicle starter switch auxiliary handle, as shown and described.

DESCRIPTION

FIG. 1 is a rear perspective view of a vehicle starter switch auxiliary handle showing my new design, the starter switch and key being shown in broken lines for illustrative purposes only;

FIG. 2 is an enlarged front elevational view thereof;

FIG. 3 is an enlarged top plan view thereof;

FIG. 4 is an enlarged rear elevational view thereof;

FIG. 5 is an enlarged left side elevational view thereof;

FIG. 6 is an enlarged right side elevational view thereof;

FIG. 7 is an enlarged bottom plan view thereof.

Fig.1.**Fig. 2.****Fig. 3.****Fig. 4.****Fig. 5.****Fig. 6.****Fig. 7.**
